CONDENSER

Lyman G. Ketcham, Brooklyn, N. Y., assignor to
 Teleradio Engineering Corporation, New York,
 N. Y., a corporation of New York

Application October 18, 1935, Serial No. 45,585

3 Claims. (Cl. 125—41.5)

This invention relates to condensers for use in radio apparatus and particularly to condensers of the type known to the art as trimmer condensers utilized for making fine adjustments in the capacity of a circuit.

This application is a continuation in part of my copending application Serial No. 743,710, filed September 12, 1934.

An object of the invention is to provide a new, simple, efficient and inexpensive condenser of very small variable capacity.

Another object of the invention is to provide a condenser of such construction that the capacity thereof can be varied by simply rotating a single control member.

A further object of the invention is to provide a condenser in which the movable plate is so constructed as to be forced away from the fixed plate normally under its own resiliency.

Another object of the invention is to provide a gang condenser assembly in which one member serves as a plate common to all the condensers in the gang.

In carrying out the foregoing and other objects of the invention a condenser is provided with a small rectangular base of some suitable insulating material, preferably of a highly compressed ceramic material which is substantially non-hygrosopic. This base is provided with a central aperture and with recesses in opposite edges thereof. The lower plate of the condenser is provided with depending tongues to fit in the recesses, and has an end portion cut away to register with the opening in the base but the cut away portion is of such size as not to contact with an eyelet passing through the opening in the base. The lower plate is provided with an aperture punched therefrom into the fashion of a burr, the walls of the aperture and of the burr being internally threaded. A strip of dielectric material is positioned on top of the lower plate. The upper plate comprises a flat metallic portion adapted to lie over the dielectric material, such portion being joined to another portion of the plate by means of separated bowed connecting strips somewhat similar to those previously described. A part of the material between the strips is moved by punching and the remaining portion is apertured and such portion is separated from the dielectric by another insulator similar to the base. The parts of the assembly, namely, the base, the lower plate, the dielectric material, the insulator and the upper plate, are secured together by means of a single eyelet passing through the assembly and headed under the base and over

the upper plate. The upper plate is provided with an aperture in alignment with the threaded aperture in the lower plate but of considerably larger diameter. A headed screw passes through the upper plate and through the dielectric into threaded engagement with the aperture in the lower plate. This screw is insulated from the upper plate by means of a washer, preferably made of the same insulating material as the base. By this arrangement, the upper plate can be forced downwardly into close contact with the dielectric, in which position the condenser has its greatest capacity but at the same time when the screw is loosened the upper strip, due to the resiliency of the bowed connecting strips, moves away from the lower plate to decrease the capacity of the condenser. This upper plate can move away from the lower plate until the ultimate minimum capacity of the condenser is reached, which capacity amounts substantially only to the capacity determined by the air gap between the plates.

A plurality of condensers made in accordance with the foregoing can be combined into a gang and, if desired, this gang can be so constructed that a single plate is common to all of the condensers in the assembly. The number of condensers in the assembly may vary as occasion demands, and a gang so constructed serves admirably in installations wherein a plurality of condensers each have one plate grounded. Thus by utilizing a common plate for all the condensers in the assembly a single ground connection to this common plate can be utilized for the entire assembly. The common plate will be provided with upstanding tongues to engage in one of the insulating blocks of each unit to accurately position the units relative to the plate.

Other features, objects, and advantages of the invention will become apparent by reference to the following detail description read in the light of the accompanying drawings, wherein

Fig. 1 is a plan view of a single condenser embodying the invention;

Fig. 2 is an end view of the same device.

Fig. 3 is a side view thereof.

Fig. 4 is a view of the other end thereof.

Fig. 5 is a section taken substantially on the line 5—5 of Fig. 1.

Fig. 6 is a plan view of a gang condenser assembly embodying the invention; and

Fig. 7 is a similar view partially fragmentary of a modified form of gang assembly.

Referring now to the drawings and particularly to Figs. 1—5 inclusive, a base 10 is provided in

the shape of a rectangular block of insulated material, preferably of some highly compressed ceramic material which is substantially non-hygroscopic. This block 10 is provided with a central aperture 11 and is provided in the opposite ends thereof with recesses 12.

The lower plate of the condenser is made up of a strip of metal 14 having one end cut away as indicated at 15 (Fig. 1). The legs 16 formed by cutting away a part of the strip have tongues 17 punched therefrom to extend downwardly and to fit into the recesses 12. The plate 14 is provided with an aperture 18 so punched therefrom as to provide a burr 19 which is internally threaded. The opposite end of the plate 14 is bent downwardly as at 20 to provide a terminal. This terminal 20 has an opening 21 therein to facilitate the attaching of conductors, and if desired it is provided with notches 22 for the same purpose.

Positioned on top of the plate 14 is a strip of dielectric material 24. The strip of material is preferably made of high quality mica. The strip 24 is provided with an opening substantially in alignment with the opening 11 in block 10 and with a second opening substantially in alignment with the aperture 18 in the lower plate. Positioned on top of the dielectric 24 and over the block 10 is an insulator 25 which for purposes of convenience may be a duplicate of the block 10.

The upper plate of the condenser assembly is made up of a metal strip having flat portion 26 overlying the dielectric material and having an opening 27 therein substantially coaxial with the aperture 18. The opening 27, however, is of considerably larger diameter than that of the aperture 18. The flat portion 26 has extending from one end thereof a pair of separated bowed connecting strips 28. Between the connecting strips 28 and formed integrally therewith is an attaching portion 29 provided with an aperture 30 in alignment with the openings in the block 10 and the insulator 25. Depending from the attaching part 29 is a terminal portion 31 having an aperture 32 and notches 33 for the attachment of conductors.

The block 10, plate 14, the dielectric 24, the insulator 25, and the attaching portion 29 of the top plate, are all locked together by means of a single eyelet 34 passing through the aligned openings in the members and headed under the block 10, and over the attaching portion 29. The opening 15 in the plate 14 is of such size as to prevent contact of the plate 14 with the eyelet, the position of the plate 14 being determined by the engagement of the tongues 17 in the slots 12 of block 10. A headed screw 40 passes through the opening 27 in the plate 26 through the opening in the dielectric 24, into threaded engagement with the wall of the threaded aperture 18 in the burr 19. This screw 40 is insulated from the upper plate by means of a washer 41 preferably made of the same material as the block 10 and the insulator 25.

With the parts assembled as shown, the condenser may have its capacity varied by adjustment of the screw 40. When this screw is tightened the upper plate 26 is forced against the dielectric 24 to cause the condenser to have its greatest capacity, while when the screw is loosened, the upper plate moves away from the lower plate and the dielectric due to the resiliency of the bowed connecting strips. This plate can move away from the lower plate until the condenser has a minimum capacity which capacity

in practice has been found to be the result almost entirely of the capacity of the air gap between the plates. Thus, the minimum range of substantially two micro-micro-farads is obtained.

The recesses 12 may be located in the upper block 25 instead of in the lower block 10 if desired, in which event the tongues 17 will extend upwardly from the lower plate 14 instead of downwardly as shown. Since the terminal flange 31 extends downwardly adjacent the edges of the blocks 10 and 25, this flange prevents turning of the upper plate about the eyelet as an axis and also aids in aligning the parts of the unit. The bowed connecting strips 28 being substantially semi-circular in form, cause the upper plate to move away from the lower plate in a manner, which, while not quite rectilinear in fashion, closely approaches being rectilinear. Thus, when the upper plate moves away from the lower plate the movement is more or less uniform, and as the result of such movement, when the plates are in their most spaced apart position the unit has been found to have the absolute minimum capacity.

In Fig. 6 a modification of the invention is shown, such modification consists of a gang condenser assembly utilizing a single metallic plate which is common to each unit of the gang. In this figure of the drawings, 50 indicates a metallic plate which is provided with upstanding flanges 51 spaced about portions of the boundary thereof to form tongues which seat in recesses in insulator blocks of the various units. In the form shown, the gang is composed of units indicated generally at 54, 55, 56 and 57. Each unit is constructed in the same fashion as the unit shown in Figs. 1 to 5, inclusive, with the exception that the plate 50 replaces the individual plates 14 which would be present in four units made up as previously described. In these units the upper block is provided with recesses for the reception of the tongues 51, which tongues serve to definitely locate the units about the plate 50 and to aid in holding the units properly aligned. A number of openings 58 are shown in the plate 50 for the purpose of mounting the plate in some convenient position relative to the chassis of a radio set.

In the arrangement shown in Fig. 7, a metallic plate 60 of strip form is provided with a plurality of upstanding flanges 61, which again provide tongues to seat in recesses in insulating blocks of the condenser units associated with the plate. These units are indicated generally at 64, 65, 66, 67 and 68. The number of units in the assembly may vary as conditions require; in actual practice assemblies having been made up in various numbers of units from two upwardly. In this assembly the plate 60 is common to each of the units 64 to 68, inclusive, replacing what would be the individual plates 14 of single units should a number of single units be arranged in gang fashion in other suitable manner.

The gang condenser assemblies shown in Figs. 6 and 7 are of especial utility in installations wherein a number of trimmer or padder condensers are used in such fashion that one plate of each condenser is grounded. In such installations a single gang assembly may be used to replace the individual condensers ordinarily used, in which event the common plate would be grounded. The upper plate of each unit would be properly connected in the circuit so that for all practical purposes the units of the gang can be adjusted independently of each other so that each unit may have the desired capacity rating.

While the aligning arrangement utilized for registering the blocks of insulating material with the lower plate have been described as consisting of tongues on the plate and recesses in the blocks, it is to be understood that other arrangements can be used. For example, any type of cooperating formations on the plate and on one or both of the blocks will suffice.

From the foregoing it will be seen that the present invention, in the various forms illustrated, provides a new, simple, efficient and inexpensive type of condenser of small variable capacity which on account of the non-hygrosopic qualities of the insulating material will retain a capacity setting in spite of atmospheric changes. It is to be understood that the invention is not to be limited to the illustrated embodiments, but is to be limited only by the scope of the following claims.

20 I claim:

1. In a trimmer condenser, the combination of a rigid metal base serving as one of the condenser electrodes, a ceramic block, said base having one end lying flat against one face of said block and interlocked therewith, a metal strip having one end in the form of a plate forming a cooperating condenser electrode with the first-mentioned electrode, the other end of said strip being bent at right angles to the first-mentioned end and joined thereto by a bowed portion, said other end having a struck-out lug disposed against the other face of said block, and means passing through said lug, said block and said base to rigidly clamp said block between said strip and said base.

2. In a trimmer condenser, the combination of a rigid metal base serving as one of the condenser electrodes, a pair of blocks of insulating material, said base having one end interposed between said blocks and lying flat against one face of one of said blocks and interlocked therewith, a metal strip having one end in the form of a plate forming a cooperating condenser electrode with the first-mentioned electrode, the other end of said strip being bent at right angles to the first-mentioned end and joined thereto by a bowed portion, said other end having a struck-out lug disposed against the outer face of one of said blocks, and means passing through said lug, said blocks, and said base to rigidly clamp 15 said blocks, base and lug together.

3. In a trimmer condenser, the combination of a rigid metal base serving as one of the condenser electrodes, a pair of blocks of insulating material, said base having one end interposed between said blocks, and lying flat against one face of one of said blocks, the contacting surfaces of the end of said base and of one of said blocks having formations cooperating to interlock said base and said block, a metal strip having one end in the form of a plate forming a cooperating condenser electrode with the first-mentioned electrode, the other end of said strip being bent at right angles to the first mentioned end and joined thereto by a bowed portion, said other end having a struck-out lug disposed against the outer face of one of said blocks, and means passing through said lug, said blocks, and said base to rigidly clamp 20 said blocks, base and lug together. 25

LYMAN G. KETCHAM. 35
